UNITED STATES PATENT OFFICE.

WALDO P. JOHNSON, OF CHICAGO, ILLINOIS.

POULTRY-CAR CONSTRUCTION.

Application filed March 3, 1927. Serial No. 172,849.

This invention relates to improvements in poultry cars and more especially to that type of poultry car provided with tiers of coops on each side of a central aisle. In cars 5 of this type, the coops ordinarily are closed on the outside by a wire screening to keep the poultry in and at the same time permit the entrance of light and air. In bad weather, however, the poultry must be shielded 10 against cold, and the elements.

One of the features of my invention is the provision of simple and efficient means for so shielding the poultry in a car of this type.

My improved car is simple in construction 15 and efficient in service.

Other features and advantages of my invention will appear more fully as I proceed with my specification.

In that form of device embodying the 20 features of my invention, shown in the accompanying drawings, Fig. 1 is a fragmentary view in side elevation of a poultry car, showing the canvas covering in position, with a portion broken away, Fig. 2 is a view taken as indicated by the line 2 of Fig. 1, Fig. 3 is an enlarged fragmentary view in side elevation showing details of my invention, and Fig. 4 is a view taken as indicated by the line 4 of Fig. 3.

As shown in the drawings, the car is provided with a plurality of vertical side posts 10 and corner posts 11. At each side of the door of the car there is arranged a door post indicated by 12. The posts are secured at 35 their lower ends to the main frame 13 of the car by means of rivets 14.

Each of the posts 10 consists of an outwardly facing channel provided with outwardly turned flanges 10^a. Within the channel of the side post 10 is secured a wood filler 15 by means of the bolts 16.

The corner posts 11 are formed of members substantially Z-shaped in cross section and within the outer angle is placed a wood 45 filler 17 supported by means of the bolts 18. The door post 12 is similar in shape and is provided with a similar wood filler 19 supported by means of the bolts 20.

Adjacent the door post 12 is another post 50 21, which is also formed of a member substantially Z-shaped in cross section and to this member is bolted an angle iron 22 by means of the bolts 23. One of the flanges 21^a of the member 21 is parallel with the 55 flange 22^a of the member 22 and both flanges

21^a and 22^a are turned to face away from the door post 12.

Each tier of coops is closed in on the outside by a long screen strip having edges preferably made of small channel bars 24. Each of these screen strips extends from the corner post 11 substantially to the door opening 25. One end of each of the screen strips is located beneath the flange 11^a of the corner post 11 and the other end lies between the 60 two flanges 21^a and 22^a of the two members 21 and 22 (see Fig. 4). The screen strips are held in position by cleats 25 bolted to the flanges 10^a of the side posts 10. Each of the cleats 25 has oppositely extending 65 fingers 25^a to overlap the members 24 of adjacent screen strips. Each of the cleats 25 is attached to the flange 10^a of a side post 10 by means of a bolt 26.

27 indicates a protective covering of canvas or similar material, adapted to be placed 70 outside of the screens on a car to protect the poultry in the coops from cold or the elements. Obviously, this canvas need not be on at all times; and consequently I have 75 provided new and improved means for readily putting on and taking off the canvas. This is accomplished by placing the canvas in position and nailing a slat or a strip 28 to the filler 17 in the corner post 11 by means 80 of the nails 29. It is to be understood that the canvas is placed under the slat 28. The canvas is similarly fastened to a filler 15 in a side post by means of the slat 30 attached by the nails 31; and at the end 85 adjacent the door opening there is provided another slat 32 attached by the nails 33 to the filler 19. It will be seen that these wood fillers 17, 15 and 19 furnish a substance to 90 which the slats 28, 30, and 32 can be readily nailed.

While I have shown and described certain 95 embodiments of my invention, it is to be understood that it is capable of many modifications. Changes, therefore, in the construction and arrangement may be made without departing from the spirit and scope of the invention as disclosed in the appended claim, in which it is my intention to claim all 100 novelty inherent in my invention as broadly as possible in view of the prior art.

What I claim as new, and desire to secure by Letters Patent, is:

A poultry car of the character described, 110 having a central aisle with coops on each

side, side posts with laterally projecting flanges, corner posts and door post members having flanges projecting toward each other, horizontal screen strips having reinforced edges, the ends of the screen strips adapted to lie under the flanges of a corner post and a door post member, and means for securing said screen strips to the car, said

means comprising a cleat, and means for attaching the cleat to the flange of a side post, said cleats having fingers adapted to overlap the reinforced edges of adjacent screen strips. 10

In witness whereof, I have hereunto set my hand this 1st day March, A. D. 1927.

WALDO P. JOHNSON.
